(57) **CLAIM**

The ornamental design for a drive carrier handle, as shown and described.

DESCRIPTION

FIG. 1 is a front perspective view of the drive carrier handle with the handle closed comprising the present invention;

FIG. 2 is a front perspective view of the drive carrier handle with the handle open comprising the present invention;

FIG. 3 is a front side view thereof;

FIG. 4 is a left side view thereof;

FIG. 5 is a right side view thereof; and,

FIG. 6 is a bottom plan view thereof.

The broken line showing of portions of the drive carrier handle is included for the purpose of illustrating environmental structure and forms no part of the claimed design.
